United States Patent Office

Des. 186,925
Patented Dec. 22, 1959

186,925

REGULATOR OR SIMILAR ARTICLE

Robert E. Zdara, Euclid, and Richard C. Krall, Willowick, Ohio, assignors to The Weatherhead Company, Cleveland, Ohio, a corporation of Ohio

Application September 2, 1958, Serial No. 52,476

Term of patent 14 years

(Cl. D78—1)

Fig. 1

Fig. 2

Fig. 3

Fig. 4

Fig. 5

Fig. 1 is a side elevation of the regulator showing our new design;

Fig. 2 is an elevational view of the regulator taken from the left of Fig. 1;

Fig. 3 is an elevational view thereof taken from the right of Fig. 1;

Fig. 4 is a top plan view of the regulator; and

Fig. 5 is a bottom plan view thereof.

We claim:

The ornamental design for a regulator or similar article, as shown.
